UNITED STATES PATENT OFFICE.

JAMES W. TAYLOR, OF SAN ANTONIO, TEXAS.

PUMPING APPARATUS.

Application filed March 16, 1925. Serial No. 15,756.

To all whom it may concern:

Be it known that I, JAMES W. TAYLOR, a citizen of the United States, residing at San Antonio, in the county of Bexar and 5 State of Texas, have invented certain new and useful Improvements in Pumping Apparatus, of which the following is a specification.

This invention relates to pumping apparatus for oil wells and more particularly to an improved apparatus of this character by the use of which oil is forced from the well by the pressure of an expansible operating fluid.

10 In accordance with the invention a pumping apparatus is employed wherein is provided a flow line or tubing through which the oil is led from the well, and wherein the flow line is constructed to include a plurality of valves for admitting the air or elevating fluid thereto, the valves being so constructed that as the flow line is raised or lowered the valves are successively opened and closed during such raising or lowering 25 operation.

Specifically, it is the object of the invention to provide new and improved apparatus for permitting of the raising and lowering of the valved flow line in a simple, positive 30 and readily controlled manner.

A further object of the invention resides in the provision of an apparatus which constitutes an improvement upon the structure disclosed and claimed in my previous Patent 35 1,509,323 and that set forth in my copending application Serial Number 643,652 filed June 6, 1923.

With these and other objects in view, as will appear as the description proceeds, the 40 invention consists in the novel features of construction, combinations of elements and arrangements of parts hereinafter to be fully described and pointed out in the appended claims.

45 In the accompanying drawing:

Figure 1 is a vertical sectional view, partly in side elevation, of the upper end of a well casing embodying a pumping apparatus constructed in accordance with the present 50 invention,

Figure 2 is a side elevation thereof,

Figure 3 is a horizontal sectional view taken on the plane indicated by the line 3—3 of Figure 1,

Figure 4 is a similar view taken on the line 4—4 of Figure 1,

Figure 5 is a vertical sectional view on the line 5—5 of Figure 2,

Figure 6 is a vertical sectional view taken through the well casing and tubing and disclosing the tubing in its lowered position 60 within the casing,

Figure 7 is a similar view disclosing the tubing in its elevated position,

Figure 8 is a vertical sectional view taken 65 on the line 8—8 of Figure 6, and showing one of the valve sections of the tubing in its closed position,

Figure 9 is a similar view disclosing the valve section of the tubing in its open or 70 gas admitting position, and

Figure 10 is a similar view showing the valve section in its second closed position.

Referring more particularly to the drawings, the numeral 10 indicates the casing of 75 a well and 11 the flow line or tubing disposed within the casing. The flow line 11 comprises a plurality of sections 12 connected by control valves 13 for controlling the admission of air, gas, or other expansible operating fluid contained within the casing to the flow line. The lowermost section 12 of the flow line is provided with a foot screen generally indicated by the numeral 15. The flow line is sealed to the casing, as 80 at 16 adjacent the upper end thereof, the seal permitting of the vertical movement of the flow line within the casing 10 without loss of gas from the well. Below the seal or packing 16, a fluid pressure inlet 17 is 85 provided through which pressure may be introduced to the casing and enter the flow line through the valves 13 hereinbefore indicated. At the upper end of the casing means are provided, generally indicated at 90 18, for lifting the flow line vertical so that the operation of the valves 13 may be controlled to govern the entrance of the lifting fluid into the flow line and the consequent elevation of the oil and the well.

The apparatus 18 comprises a head 19 which is threaded as at 20 upon the upper end of the casing 10. The head 19 is formed with an axial opening for the reception of the flow line 11, and this opening is enlarged to receive the packing 16 which is maintained in firm engagement with the flow line by means of a threaded nut 21.

The tubing extends upwardly through the packing 16 and near its upper end is formed with a collar 22, which engages with a cross head 23. The outer ends of the cross head 23 are formed with depending studs 24 which are received within the open upper ends of vertically depending rods 25. The rods 25 extend downwardly and axially through cylinders 26 carried by the head 19 and disposed on opposite sides of the flow line 11. These cylinders have their lower ends closed by means of threaded plugs 27, which are provided with depending studs 28 that are positioned within relatively enlarged openings 29 formed in connection with the head 19. The lower ends of the rods 25 are threaded and secured to pistons 30 that are mounted for vertical reciprocation within the cylinders 26. Each piston 30 includes a base section 31, provided with an annular shoulder upon which seats a ring 32, the latter being held in place by the upper section 33 of the piston which forces downwardly upon the ring 32 by means of pressure exercised by nuts 34 carried in connection with upwardly extending stud bolts 35, that are carried by the base section 31.

Adjacent to the casing 10 there is disposed a liquid tank 36 from the bottom of which leads a pipe 37, provided exteriorly of the tank within a control valve 38, and above the valve 38 the pipe line 37 is branched as indicated at 39 and arranged to enter the lower portions of the cylinders 26 as designated by the numeral 40. Also provided in connection with the tank 36 is an air inlet pipe 41 in which is mounted a valve 42. The pipe 41 leads from a source of fluid supply under pressure, and the valve 42 is employed to control the flow of the fluid through the pipe 41 and into the tank 36. Also arranged in communication with the line 41 is a relief valve 43 by means of which fluid pressure in the tank may be regulated. Manifestly, when the valve 43 is closed, the opening of the valve 42 will admit gas under pressure in the tank 36. This pressure is exercised upon the upper surface of the liquid in the tank so that said liquid is forced through the pipe line 37, past the valve 38 and into the cylinders 26, causing the rise of the pistons 30 mounted therein. The movement of the pistons is transmitted to the rods 25 and thence to the yoke or cross head 23, and since the latter is in engagement with the collar 22, it follows that the tubing or flow line 11 of the well will be raised in unison with the pistons. Near the upper end of the cylinders 26 the walls of the latter are formed with relief ports 44 by means of which the extent of rise of the pistons may be governed. When it is decided to lower the flow line, the valve 42 is closed and the valves 38 and 43 opened. The

weight of the flow line, acting on the pistons causes the liquid to return to the tank 36, permitting of a controlled and gradual descent of the flow line.

Threaded upon the packing nut 21 is a vertically disposed sleeve 45, which has its upper end threaded to receive an annulus 46 in which is provided an inverted frustoconical socket 47. This socket is arranged to receive a plurality of automatically operating flow line gripping or wedge sections 48 by means of which the flow line may be maintained in a suspended condition within the casing 10 independently of the support normally provided by the cross head 23 and its associated hydraulic raising and lowering mechanism. The sections 48 are preferably formed from high grade steel and have their outer faces conically inclined to co-act in a wedge-like manner with the face of the conical socket 47. The inner faces of the sections 48 are formed with gripping teeth 49, which assist in enabling the sections 48 to exercise and secure a positive hold upon the outer cylindrical surface of the tubing. Each of the sections 48 includes an upwardly extending bolt 50 which is positioned within a collar 51 loosely surrounding the tubing 11. It will be seen that when the sections 48 are positioned within the socket 47, as shown in Figure 1, and liquid pressure removed from the cylinders 26, the weight of the tubing or flow line will force the sections 48 securely into the sockets 47, and since this socket is in the form of an inverted cone, it follows that the relatively movable sections 48 will be firmly contracted around the tubing 11, gripping the latter with sufficient pressure to prevent the tubing from slipping downwardly in the casing. In fact, the weight of the tubing serves to insure a firm and positive grip on the part of the wedges 48. When the wedges are not supporting the tubing, the collar 51 is elevated together with the wedges and by means of a set screw 52, the collar may be secured in connection with the tubing with the wedges out of active relation with the annulus 46.

The upper end of the flow line is provided with a curved fitting 53 which is provided with a depending pipe section 54 adapted to be slidably received within the upper end of a stationary pipe line 55 which constitutes a continuation of the flow line. The upper end of the pipe section 54 carries a packing 56 by means of which fluid escape between the movable and stationary parts of the flow line is prevented. The lower end of the pipe line 54 is mounted within an adjustable block 57, carrying a projection 58 which is received within a socket formed in connection with the head 19. The socket includes a set screw 59 which maintains the block 57 against movement. By the provision of

the adjustable block it is convenient to maintain proper registration between the pipe sections 54 and 55, preventing binding of these relatively movable parts and improper registration. The curved fitting 53, in registration with the flow line 11, may be provided with a removable packing gland 60 through which may be led a line 61 which carries at its lower end a brush 62. This brush may be raised and lowered throughout the length of the flow line 11 so as to clean the latter of the deposit, usually paraffin, which accumulates upon the walls of the flow line and tends to interfere with the free flowing of the liquid. It will be observed that the flow line is devoid of obstructions of any nature so that the rise and fall of the cleaning brush 62 will not be interfered with or obstructed in any manner.

The flow line, as shown in Figures 6 to 10 inclusive consists of a plurality of pipe sections wherein the lower ends of which are designated by the numeral 63 and the upper ends by the numeral 64. Uniting the ends 63 and 64 are couplings 65 which in reality comprise the valves 13. These couplings are located at suitable spaced distances in the length of the flow line and since the same are of similar construction, a description of one will suffice for all. Each coupling comprises a sleeve 66, which is threaded as at 67 upon an annular enlargement 68 provided upon the lower end 63 of the flow line sections. The lower end of each sleeve 66 is provided with an annular enlargement 69, and the opposed faces of the enlargements 68 and 69 are reversely beveled to provide valve seats 70 and 71. The upper ends 64 of each top section that projects into a coupling 65 is formed with an annular enlargement 72, the ends of which being beveled as at 73 to correspond to the beveled surfaces 70 and 71, so that while the seats 70 and 71 are engaged, as shown in Figures 8 and 10, with the surfaces 73 fluid flow through the valves or couplings will be prevented. By reference to Figure 9 it will be seen that the diameter of the enlargement 72 is slightly less than the internal diameter of the sleeve 66 so as to provide a gas passage therethrough. Similarly, the enlargements 69 on the lower end of the sleeve 66 possesses a greater diameter than that of the tubing section to permit of fluid flow, is indicated in Figure 9.

In accordance with this structure an improved apparatus is provided for removing conveniently and practically oil from the flow line of a well. In starting the apparatus air pressure is introduced in the casing by way of the inlet 17. This pressure which is maintained uniformly, is exerted upon the surface of the liquid in the casing 10, causing said liquid to be forced downwardly from its natural level in the casing and rise

correspondingly in the flow line. Then, in order to remove by easy stages the column of liquid in the flow line, the valves 13 are operated successively, beginning with the upper valve and proceeding downwardly the full depth of the well, in such manner that the liquid disposed between the valves will be removed from the flow line by successive stages and through the cooperative influence of the fluid pressure introduced in the well casing. Thus, when the well is initially started the upper of the valves 13 is opened. Since this valve is above the liquid level in the casing, the expansible operating fluid will circulate through said upper valve due to the fact that the pressure in the casing exceeds the pressure in the liquid line above the nozzle or valve through which the fluid is passing. Due to the weight of the column of liquid above the valve, the fluid will not expand immediately upon entering the flow line but will rise by virtue of its natural buoyancy and will continue to expand gradually as the liquid pressure near the top of the flow line gradually diminishes, so that when the gas pressure will have reached the upper end of the flow line the expansion thereof will be so great as to produce enlarged gas bubbles which moving rapidly and in quick succession force the liquid from the upper end of the flow line. As the liquid is withdrawn from the flow line and the pressure is continued in the casing the liquid level in said casing gradually recedes, until the next lower nozzle is uncovered. At this point of operation the upper nozzle is closed, and the next adjacent lower nozzle is opened and the action above described is repeated until the liquid has been forced out of the tubing between said adjacent nozzles and is receding again in the flow line to uncover the third of the nozzles. This action is continued successively until all of the nozzles or valves 13 have been opened and closed, and the liquid in the well has finally reached a point wherein the air pressure in the casing balances the natural inflow of the liquid into the well and the liquid contained in the flow line. This normal level of the liquid in the casing that is, the level which may be said to be the working level, is below the lowermost of the nozzles or valves 13 and usually below one or both of the aperture couplings 74 provided in said flow line. The apertures 75 in the couplings 74 are proportioned so that a restricted quantity of the expelling fluid may continually enter the flow line to remove liquid from the well as previously described.

By the provision of the raising and lowering mechanism a convenient control is provided for effecting the operation of the well tubing and valves as above related and wherein the laborious manual work heretofore involved in this operation has been

eliminated and a structure provided which can be operated more quickly and accurately. One of the rods 25 may be provided with a scale 76 movable with respect to an 5 adjustably mounted pointer 77, by means of which visual indication outside of the well may be provided as to the positions of the flow line and the valves 13 therein, indicating when said valves are opened and 10 closed.

It will be observed that the seats 70 and 71 and the surfaces 73 are beveled so as to provide for very secure and positive engagement when the valve is closed and also 15 to admit of relative disalignment of the pipe sections of the tubing without interfering with the operation of the couplings.

What is claimed is:

1. In oil well apparatus, a casing, a flow 20 line vertically shiftable within the casing, means operated by vertical shifting of the flow line for successively placing spaced points within the flow line in communication with the casing, the casing being in 25 communication with a source of fluid pressure, a means for vertically shifting the flow line, said means consisting of a cross member mounted on said flow line above said casing, piston rods depending from 30 said cross member, pistons carried by the lower ends of said rods, spaced cylinders disposed on opposite sides of said flow line and in which said pistons are mounted for reciprocation, and means operating to apply 35 or remove fluid pressure to and from the pistons in said cylinders to raise and lower said flow line.

2. In oil well apparatus, a casing, a flow 40 line mounted to shift vertically within said casing, a packing gland provided in the upper end of said casing for the slidale reception of said flow line, and fluid pressure operated means carried by the upper end of said casing and disposed on opposite sides of said flow line for controlling the vertical shifting of said vertical flow line.

3. In oil well apparatus, a casing, a head 50 provided on the upper end of said casing, a packing gland provided in said head, a flow line shiftable vertically with respect to said casing, the upper end of said flow line being extended through and above said packing gland, a pair of cylinders mounted on said head, pistons mounted within said cylinders, connections between said pistons and said flow line, and means for controlling the flow of a fluid under pressure into and out of said cylinders to raise and lower 60 said pistons and flow line.

4. In oil well apparatus, a casing, a flow 65 line vertically reciprocable in said casing, a cylinder, a piston in said cylinder, connections between said piston and flow line, a liquid reservoir, a pipe connection extend-

ing between said reservoir and said cylinder, and means permitting of the application of gas pressure to the liquid in said reservoir to control the operating positions of said piston. 70

5. In oil well apparatus, a casing, a flow line shiftable vertically with respect to said casing, a cylinder, a piston slidably mounted in said cylinder, connections between said piston and said flow line to cause the latter 75 to travel in unison with said piston, a liquid reservoir located below said piston, a valved pipe connection between the lower ends of said cylinder and reservoir, and means for applying and removing gas pressure from 80 the surface of the liquid in said reservoir to regulate the flow of the liquid into and from said cylinder.

6. In oil well apparatus, a casing, a flow 85 line mounted for vertical reciprocation relatively to said casing, a head on the upper end of said casing, a pair of cylinders mounted upon said head and disposed on opposite sides of said flow line, pistons mounted within said cylinders, connections 90 between said pistons and said flow line, and means for admitting a fluid under pressure into said cylinders to govern the working positions of said pistons and flow line. 95

7. In oil well apparatus, a casing, a flow 100 line vertically shiftable with respect to said casing, a head mounted on said casing, cylinders mounted on said head, pistons mounted for vertical reciprocation within said cylinders, fixed stems arising from said 105 pistons, and a cross member carried in connection with said flow line and cooperative with the upper ends of said stems to control the rise and fall of said flow line in unison with said pistons. 110

8. In oil well apparatus, a casing, a flow 115 line shiftable vertically with respect to said casing, means operated by vertical shifting of the flow line for successively placing spaced points within the flow line in communication with the casing, fluid pressure operated means for vertically shifting the flow line, and means for holding the flow line in a stationary position of vertical adjustment independently of the fluid pressure operated means for shifting the flow line. 120

9. In oil well apparatus, a casing, a flow 125 line vertically movable with respect to said casing, fluid pressure operating means for vertically shifting said flow line, and a plurality of wedge shaped gripping devices for maintaining said flow line in fixed positions of vertical adjustment independently of the fluid pressure operated means for raising and lowering the same.

10. In oil well apparatus, a casing, a flow 130 line passing through said casing and vertically shiftable with respect thereto, fluid pressure operating means cooperative

with said flow line for effecting the raising and lowering thereof, a tube arising from said casing and having a conical socket in the upper end thereof around said flow line, and a plurality of wedge shaped gripping devices cooperative with said socket to exercise a frictional grip upon said flow line to effect the support and expansion of the latter within said casing independently of the fluid pressure operating means.

11. In oil well apparatus, a casing, a

flow line vertically shiftable with respect to said casing, fluid pressure operating means for vertically shifting the flow line, and a normally closed entry provided in the upper portion of said flow line and adapted to permit of the insertion of a cleaning tool within said flow line to permit of the cleaning of the flow line without stopping liquid circulation therethrough.

In testimony whereof I affix my signature.

JAMES W. TAYLOR.
